FOLDING WARDROBE, CUPBOARD, AND THE LIKE

Filed June 18, 1925

2 Sheets-Sheet 2

Inventor:
Charles Allan Jones
By Agent, Inc. 3/14/26

UNITED STATES PATENT OFFICE.

CHARLES ALLAN JONES, OF GLOUCESTER, ENGLAND:

FOLDING WARDROBE, CUPBOARD, AND THE LIKE.

Application filed June 18, 1925. Serial No. 37,937.

To all whom it may concern:

Be it known that I, CHARLES ALLAN JONES, a subject of the King of Great Britain, residing at Bohanam House, Barnwood Road, Gloucester, England, have invented Improvements in or Relating to Folding Wardrobes, Cupboards, and the like, of which the following is a specification.

My invention is for improvements in or relating to folding wardrobes, cupboards, and the like, and has for its object the provision of an article of furniture or structure of this character which shall be simple and cheap to manufacture, strong and rigid when set up, roomy and efficient in use, adapted to collapse substantially flat into a minimum space for storage or transport when not required in use, and which can be set up or dismantled with great facility and without the necessity for skilled labor of any kind.

According to this invention there is provided a folding wardrobe, cupboard, or the like which comprises an upright back or foundation member, a pair of side members hingedly carried by said back, a pair of front door members hingedly carried by said sides, top and bottom members hingedly carried by said back so as to be adapted for rebated engagement with said sides, and a pair of front flap members hingedly carried by said top and bottom members so as to be adapted for rebated engagement with said sides and with the upper and lower edges of said doors, and means for fastening the various hinged members in their open position of use, the arrangement being such that the various hinged members are adapted to fold in substantially flat superposed relation upon said back member as a foundation.

The invention further provides a construction, as set forth in the preceding paragraph, wherein the parts are secured in their position of use by screw devices carried by said top and bottom front flap members.

The invention still further provides a construction, as set forth in the last preceding paragraph, wherein the hinge joints for the doors include intermediate hinge strips, which hinge strips have oppositely disposed sets of hinges and are adapted for fastening engagement with said screw devices.

The invention still further provides a folding wardrobe or like construction, as set forth in any of the three last preceding paragraphs, which comprises in addition a com-

bined detachable hanger and stay rod device.

In order that my invention may be clearly understood and readily carried into practice, reference may be had to the appended drawings upon which:

Figure 1 is an elevation in perspective of a folding wardrobe in accordance with the invention, showing the same set up in its position of use.

Figure 2 is a sectional side elevation of the same.

Figure 3 is a sectional plan of the same.

Figure 4 is a sectional side elevation of the wardrobe in its collapsed and folded position.

Figure 5 is a sectional plan of the same.

Figure 6 is a detail front elevation of an upper front corner joint of the wardrobe.

Figure 7 is a side elevation of Figure 6, in section on the line 7—7 thereof.

Figure 8 is a plan of Figure 6, in section on the line 8—8 thereof.

Figure 9 is a detail sectional plan of a front side joint of the wardrobe.

Figure 10 is an internal detail view of a catch member as applied to one of the doors.

Figure 11 is an elevation in perspective of a combined hanger and stay rod device for the wardrobe as hereinafter referred to.

In a convenient embodiment of the invention, as applied to a folding wardrobe or the like, an upstanding back or foundation member *a* of rectangular framed construction is provided, having forwardly projecting fixed hinge strips *b* and *b*¹ at its top and bottom edges respectively. To the upright side edges of this back member *a*, within the top and bottom fixed hinge strips *b* and *b*¹, are hinged respectively on inward hinges *c* and *c*¹ a pair of side members *d* and *d*¹, also of rectangular framed construction. To the upright outer or forward edges of these side members *d* and *d*¹ are hinged respectively a pair of front door members *e* and *e*¹ of rectangular framed or other construction, of a length somewhat less than that of the hinged sides *d* and *d*¹ so as to terminate at short distances from the top and bottom thereof. These hinge joints for the doors are of a character adapted to permit of a hinging movement through an angle of 270°, to thereby enable the pair of doors *e* and *e*¹ to be swung outwardly from their aligned position of use into ex-

ternal facial relation to the side members d and d^1 by which they are respectively carried, for this purpose the hinge joints being of twin formation, that is to say, including narrow intermediate bevelled hinge strips f and f^1 respectively, with hinges g and g^1 in oppositely disposed sets on the respective hinge strips.

To the forward edge of the fixed hinge strip b at the upper end of the back or foundation member a is hinged on downward hinges h a top or cover member i of rectangular formation, this top member i being internally rebated along its side edges as at j and j^1 for jointing engagement with the upper edges of the respective side members d and d^1 . To the forward or outer edge of this top member i is hinged on downward hinges k an upper front flap member l of comparatively narrow rectangular formation, this flap member l being internally rebated at each end as at m (Figures 6 to 8) for jointing engagement with the front edges of the respective side members d and d^1 and with the upper ends of the respective hinge strips f and f^1 , and being externally rebated along its lower or outer edge as at n for jointing engagement with the upper edges of the pair of doors e and e^1 , the said upper front flap member l thereby constituting a kind of hinged transom for the doors.

To the forward edge of the fixed hinge strip b^1 at the lower end of the back or foundation member a is hinged on upward hinges h^1 a base member i^1 of similar form to the top or cover member i , this base member i^1 having hinged to its forward edge on upward hinges k^1 a lower front flap member l^1 of similar form to the upper front flap member l , this base member i^1 being adapted for rebated engagement at o and o^1 with the pair of side members d and d^1 , and the lower front flap member l^1 being adapted to provide a kind of rebated sill for the pair of doors e and e^1 . The upper and lower front flap members l and l^1 are each adapted to carry a pair of fastening devices, one at each end, consisting for example of a simple screw p adapted to pass through the flap and into a striking plate q provided within the rebated upper end of the corresponding hinge strip f or f^1 , or alternatively consisting of a suitable bolt and thumb-screw device.

The wardrobe or the like, when set up in its position of use, as shown in Figures 1 to 3, is adapted to be secured simply by an adjustment of the four screw fastenings p . When the structure is required to be folded up, the fastenings p are released, the doors e and e^1 are folded outwardly upon the sides d and d^1 , the cover i and base i^1 are slightly opened, and the folded sides d and d^1 and doors e and e^1 are then in-

folded upon the back or foundation a , the cover i and base i^1 being finally folded down upon the facially superposed doors e and e^1 , sides d and d^1 , and back a , the entire structure being thus disposed in substantially flat rectangular formation, as shown in Figures 4 and 5, so as to occupy a minimum space for storage or transport.

A combined hanger and stay rod r may be fitted longitudinally within the upper part of the wardrobe, this rod being detachably secured, together with external hooks s , by means of terminal nuts t , and being additionally supported at an intermediate point by means of a folding lug u having a pivoted suspension from a slotted plate v fixed to the inner face of the top or cover member i . The doors e and e^1 may be provided respectively with catch w and lock x .

In the case of a cupboard or the like where shelves are required, these may be detachably fitted, or they may be hingedly carried by the back or foundation member, in which latter case the hinged joints of the side members may be suitably raised, for example by forwardly projecting fixed hinge strips, to provide for the extra depth of the superposed parts when collapsed and folded up.

The invention, although mainly applicable to wardrobes, cupboards, and like articles of furniture, may be readily adapted to poultry houses and like structures of collapsible or folding type, the construction in this case being suitably modified to provide for the usual inclined roof.

What I claim as my invention and desire to secured by Letters Patent is:—

1. A folding wardrobe, cupboard, or the like which comprises, in combination, an upright back or foundation member, a pair of side members hingedly carried by said back, a pair of front door members hingedly carried by said sides, top and bottom members hingedly carried by said back so as to be adapted for rebated engagement with said sides, a pair of front flap members hingedly carried by said top and bottom members so as to be adapted for rebated engagement with said sides and with the upper and lower edges of said doors, and means for fastening the various hinged members in their open position of use, the arrangement being such that the various hinged members are adapted to fold in substantially flat superposed relation upon said back member as a foundation.

2. A folding wardrobe, cupboard, or the like as specified in claim 1, wherein the parts are secured in their position of use by screw devices carried by said top and bottom front flap members.

3. A folding wardrobe, cupboard, or the like as specified in claim 1 wherein the parts

are secured in their position of use by screw devices carried by said top and bottom front flap members and wherein the hinge joints for the doors include intermediate hinge strips, which hinge strips have oppositely disposed sets of hinges and are adapted for fastening engagement with said screw devices.

4. A folding wardrobe, cupboard, or the

like, as specified in claim 1, wherein the 10 parts are secured in their position of use by means carried by said top and bottom front flap members, and comprising in addition a combined detachable hanger and stay rod device.

In witness whereof I have hereunto set my hand.

CHARLES ALLAN JONES.
